UNITED STATES PATENT OFFICE.

LOUIS ROSEBUSH, OF LINWOOD, MICHIGAN, ASSIGNOR OF ONE-HALF TO THOMAS R. BOYLE, OF LINWOOD, MICHIGAN.

CAR-STAKE.

1,168,560.

Specification of Letters Patent. Patented Jan. 18, 1916.

Application filed March 12, 1915. Serial No. 13,867.

To all whom it may concern:

Be it known that I, LOUIS ROSEBUSH, a citizen of the United States of America, residing at Linwood, in the county of Bay and State of Michigan, have invented certain new and useful Improvements in Car-Stakes; and I do hereby declare the following to be a full, clear, and exact description of the invention, such as will enable others skilled in the art to which it appertains to make and use the same.

This invention relates to a car stake construction adapted to be applied especially to flat cars.

15 The primary object of the invention is to provide a construction of this character in which the car stakes may be located and releasably retained in upright position so as to hold articles carried on the car against lateral displacement.

20 It is a further object of this invention to provide the stake with means whereby it may be released from upright position and permitted to fall and occupy a space below the car bottom; while a still further object is to provide a retaining device which may be operated at a distance from the stake so that when the stake is released to fall to lower position the operator will be at a distance from the staple and any danger liable to occur from the falling stake will be eliminated.

25 Various other objects and purposes consisting in novel and useful details of construction and operation will be apparent upon understanding of the embodiment illustrated in the accompanying drawing, in which—

30 Figure 1 is an end elevation of a car provided with my improved car stake. Fig. 2 is a partial sectional and side elevation showing the stake in its operative upright position. Fig. 3 is a similar view showing the stake turned down in its lower inoperative position. Fig. 4 is a plan view thereof; and Fig. 5 is a front elevation of the stake and the supporting brackets therefor.

35 Like reference characters refer to like parts throughout the several views of the drawing.

40 The car stakes are adapted to be applied at either side of the car which is shown at A in Fig. 1, the car including in its construction side frame members 1 to which at intervals 45 may be attached the brackets 2 which

are secured to the members 1 by means of bolts 3 as shown. For each stake a pair of brackets are required and the adjacent vertical sides 4 thereof are spaced a distance apart equal to the width of the stake 5 which is pivotally mounted between and carried by the sides 4, a bolt 6 extending through said sides and the lower end of the stake to provide the pivotal mount. It will be evident that with this construction the stake 5 has a 50 pivotal movement through an arc of substantially 180 degrees and may occupy the position shown in Fig. 2 where it is in upright position with the body thereof extending above the bottom of the car, or the position shown in Fig. 3 where the stake lies vertical but substantially opposite to the position that it occupies in use. A latch mechanism is used to retain the stake in upright position.

55 Spaced apart arms 7 are pivotally connected to the stake 5 on the cross rod 7^a and extend forward, the front ends thereof being connected by a handle 8. Between the ends of the arms a plate 9 is located and 60 rigidly attached in any suitable manner to the arms. This plate is positioned vertically, its lower edge extending a distance below the lower edges of arm 7, and is adapted to be received in the alined notches 10 65 formed in the upper edges of sides 4 of the brackets 2.

70 Referring to Fig. 2, with plate 9 seated in notches 10, it is evident that the stake is secured against outward pivotal movement and will be retained in position as long as plate 9 seats in said notches. To permit the movement of the stake to the inoperative position illustrated in Fig. 3, handle 8 may 75 be grasped and the latch mechanism as a whole elevated carrying the plate 9 above notches 10, whereupon the stake will be free to fall. When the car is loaded as shown in Fig. 1 the pressure exerted by the load on the inner sides of the stake will tend to 80 prevent any raising of the latch by reason of the frictional engagement of the plate against the sides of the notches but when the load has been removed, the latch can be readily operated. In practice I prefer to 85 detachably connect a chain 11 in any suitable manner to the handle 8 as shown in Fig. 1, whereby on taking hold of the free end of the chain it may be thrown upwardly to elevate the latch mechanism and free the 90

stake to move to inoperative position, the operator of the chain being far enough away from the stake to be out of its path of travel as it falls. Accidents by this means 5 are practically eliminated.

The stake 5 is preferably formed from metal as an open ended tube in which may be inserted an extension if at any time the load carried by the car reaches a height requiring the extension. A stake construction made according to this disclosure is very strong and durable and able to withstand the rough usage to which it is necessarily subjected. The latch mechanism is simple 10 and easily operated and the stakes when not in use may be lowered to inoperative position leaving the upper surface of the car free until such time as the stakes are again to be put to use.

15 Various changes in minor detail may be resorted to without departing from the invention which is defined in the appended claims and which includes all modifications falling within their scope.

20 25 I claim:—

1. A car stake construction comprised of supporting brackets having sides spaced apart and each provided with a notch in its upper edge, a stake pivotally mounted between the sides, and means mounted on the stake adapted to seat in the said notches to retain the stake in upright position, substantially as described.

2. In combination, supporting brackets 30 having adjacent sides spaced apart and each provided with a notch in its upper edge,

a stake pivotally mounted between the brackets, and a catch pivotally mounted on the stake adapted to detachably engage the sides of the brackets and seat in the notches 40 thereof, to retain the stake in rigid relation to the brackets, substantially as described.

3. In combination, a support including spaced apart vertical side members, each provided with a notch in its upper edge, a 45 stake pivotally mounted between the side members, spaced apart arms lying one at either side of the stake and pivotally connected thereto and a plate secured to and carried between the arms adapted to seat in 50 the said notches when the stake is in upright position, substantially as described.

4. In combination, a support including spaced apart vertical side members each provided with a notch in its upper edge, a 55 stake pivotally mounted between the side members, arms lying one at either side of the stake and pivotally connected thereto, the free ends of the arms extending a distance in front of the stake, a handle connecting the free ends of the arms, and a plate secured to and carried between the arms adapted to seat in the said notches when the stake is in upright position but readily disengageable therefrom to release 60 the stake, substantially as described.

In testimony whereof I affix my signature in presence of two witnesses.

LOUIS ROSEBUSH.
